UNITED STATES PATENT OFFICE.

ALBERT G. MAHRINGER, OF ST. LOUIS, MISSOURI.

DAUBER FOR BLACKING, POLISH, AND THE LIKE.

1,098,813.

Specification of Letters Patent.

Patented June 2, 1914.

Application filed April 2, 1913. Serial No. 758,481.

To all whom it may concern:

Be it known that I, ALBERT G. MAHRINGER, citizen of the United States, and resident of St. Louis, Missouri, have invented certain new and useful Improvements in Daubers for Blacking, Polish, and the like, of which the following is a specification.

This invention relates to improvements in daubers for blacking, polish and the like and 10 has for its object a pad mounted around a stiffening plate and a handle supported thereon by which the device can be readily used.

A further object is to provide a dauber 15 which is especially adapted to be placed in the box containing the polish or blacking and to remain therein when not in use.

Figure 1 is a perspective view of a blacking box with my improved dauber therein. 20 Fig. 2 is a vertical sectional view of box and dauber. Fig. 3 is a perspective view of my improved dauber disconnected showing the several parts and their construction. Fig. 4 is an enlarged fragmental sectional view 25 showing the connection of the parts.

In carrying out my invention I provide a dauber constructed of three parts, a pad 5 of felt or other fabric, a stiffening plate 6 and a handle 7.

30 The stiffening plate 6 which forms the rigid body portion of the dauber is provided with a plurality of burs 8 preferably stamped out of the material arranged as shown and are bent upwardly so that the 35 ends or flaps 9 of the pad 6 can contact therewith and be pressed down permitting the burs to penetrate the pad.

When the ends of the pad are passed over the burs the edges 10 of the flaps contact as 40 shown. The handle 7 which is preferably of a link form as shown is placed upon the pad and between the projecting burs. The burs are then bent downwardly over the bottom strand 11 of the handle in the form of loops 45 or hooks 12 acting as hinges to support the handle as well as to permit the same to assume a horizontal as well as a vertical position.

The dauber constructed as described is 50 especially adaptable for use in connection with blacking or polish in containers and is to remain therein when not in use and to be

covered by the lid 13 of the container 14. By this arrangement a dauber is at all times convenient, and by means of its handle the 55 pad can be brought in contact with the blacking or polish and the same applied on the shoes.

The body portion of the dauber can be constructed of any shape as found desirable 60 in order to properly fit into the receptacle.

Having fully described my invention what I claim is:

1. A dauber comprising a central stiffening member, a pad located around the same 65 and a looped handle attached to the stiffening member.

2. A dauber comprising a pad folded upon itself, a stiffening plate located between the folds and a looped handle attached 70 thereto.

3. A dauber comprising a pad of fabric, having its ends folded together, a stiffening plate, burs formed on the plate and projecting through the pad, and a looped handle 75 supported by the burs.

4. A dauber comprising a fabric body the same bent so that its ends contact, a plate located in the body and beneath the folded ends, burs stamped out of the plate and 80 penetrating the bent ends, a link handle located on the body and held movably between the burs, substantially as specified.

5. A dauber for use in blacking boxes comprising a folded pad, a stiffening member 85 located between the folds, and a folding handle supported thereon, substantially as specified.

6. A dauber comprising a soft pad the ends bent over on itself so as to contact, a 90 stiffening plate located between the folds and the pad, integral burs formed in the plate and arranged to project through the folded ends, a handle in the form of a loop placed over the pad and held by the burs 95 being bent over the horizontal member of the loop, substantially as specified.

In testimony whereof, I have signed my name to this specification, in presence of two subscribing witnesses.

ALBERT G. MAHRINGER.
